UNITED STATES PATENT OFFICE.

ALFRED A. ZIEGLER, OF BOSTON, MASSACHUSETTS.

JUNCTION-BOX.

1,308,830.

Specification of Letters Patent.

Patented July 8, 1919.

Application filed November 6, 1915. Serial No. 60,107.

To all whom it may concern:

Be it known that I, ALFRED A. ZIEGLER, a citizen of the United States, residing at Boston, in the county of Suffolk and State 5 of Massachusetts, have invented an Improvement in Junction-Boxes, of which the following is a specification.

This invention relates to improvements in junction-boxes.

10 It has heretofore been customary in the construction of junction-boxes of the type here shown, to permanently secure the main cables against movement through the bottom-plate, by forming recesses in the bottom-plate around the cables, and filling 15 such recesses with solder or an equivalent binding agent. The labor cost of such construction is large, for the solder or other binder must be applied after the assembly of 20 the box, or after the panel-boards and cable-housing have been mounted on the bottom-plate.

One of the objects, therefore, is to provide 25 a junction box having its panel-boards and cable-housing removably secured to the bottom-plate, which plate is itself removably secured to the casing, and having a recessed block, wherein the solder is deposited, which is removably secured to the bottom- 30 plate. By this construction, the cables may be passed through the recessed block, and united therewith by the binding material; the panel-boards and cable-housings may be secured upon the bottom-plate, and inserted 35 in the casing as a unit, and the cable-block finally secured thereto.

Another object is to provide a novel form 40 of cover-plate for the box which will efficiently guard against the entrance of rain, snow, and the like, into the box, but does not require the use of complicated and expensive sealing ribs, frames, gaskets, or the like.

Still another object is to provide a junction-box having doors of such construction 45 that complete access may be readily had to both the front and rear sides of the panel-boards and cable-housing.

The above and other incidental objects of 50 a similar nature which will be hereinafter more specifically treated, are accomplished by such means as are illustrated in the accompanying drawings, described in the following specification, and then more particularly pointed out in the claims which are ap-

pended hereto, and form a part of this application.

Figure 1 is a view in front elevation with portions of the front wall broken away, to more clearly illustrate the interior arrangement of the box. 60

Fig. 2 is a section on the line 2—2 of Fig. 1.

Fig. 3 is a top plan of the cover plate.

Fig. 4 is a bottom plan of the cover plate. 65

Fig. 5 is a section on the line 5—5 of Fig. 3.

Fig. 6 is a top plan of the bottom plate.

Fig. 7 is a section on the line 7—7 of Fig. 6. 70

Fig. 8 is a bottom plan of the bottom plate.

Fig. 9 is an end elevation of the bottom plate.

Fig. 10 is a detail view illustrating particularly the fastening means whereby the panel-boards are secured to the bottom-plate, which latter member is shown in transverse section. 75

Fig. 11 illustrates the means employed in 80 securing the cable-housing to the box-plate.

Fig. 12 is a section on the line 12—12 of Fig. 11.

Fig. 13 is a transverse section of a modified form of the bottom plate. 85

Fig. 14 is a transverse section of a further modified form of the bottom plate.

Fig. 15 is a section on the line 15—15 of Fig. 8. 90

The junction-box here shown for illustrating my invention, includes a substantially rectangular upright casing A, having a cover-plate B, which serves as a top-closure, a bottom-plate C, a housing D for the main cables, and a pair of panel-boards E. 95

The casing A includes a rear-wall 10, side-walls 11, 12, and a front-wall which is composed of two complementary sections 13, 14. The sections 13 and 14 are respectively fixed to the forward edges of the side-walls 11 and 12, and said side-walls are hinged, as at 15, to the side of the rear-wall 10. A hasp 16, or other fastening-means, is provided for the two sections of the front-wall. By making the two sections of the front-wall 100 fixed with respect to the side-walls, and hinging these members to the rear-wall, access may be had to the panel-boards and cable-housing with unusual facility. 105

The cover-plate B (see Figs. 3, 4, and 5) 110

is here shown as rectangular, and has upon its upper face the intersecting strengthening webs 18, which terminate in corner bosses or blocks 19. The area of the cover-plate is greater than the cross-sectional area of the casing, so that its marginal portions extend outwardly over the top of the walls of the casing, to effectively guard against the entrance to the casing of rain, 5 snow, melting ice, and the like.

A flange 20, is formed on the rear edge of the cover-plate which extends downward and engages the outer face of the rear-wall 10; and a pair of parallel side-flanges 21 and 22, and a front-flange 23, extend downward from the lower face of the cover-plate, the flanges 21 and 22, engaging the inner faces of the side-walls 11 and 12, respectively, and the flange 23 engaging the inner faces of the front sections 13 and 14. These flanges serve to hold the cover-plate against displacement, and also to hold the movable walls of the casing in closed position, and 20 also serve as sealing-means for preventing 25 the entrance of moisture into the casing.

The rear ends of the flanges 21 and 22 are equidistantly spaced from the flange 20, see Fig. 4, so that the upper edge of the rear-wall 10, may be disposed in said space.

30 It oftentimes happens that rain, melting snow or ice, or water of condensation, collects upon the cover-plate, and runs over the edge of the same, and because of surface cohesion, passes across the lower face of the 35 marginal portions thereof, and enters the casing at the top. To effectually guard against this trouble, an isolated draining groove 24, is provided, see Figs. 1, 2, and 4, in the lower face of the cover-plate, which 40 extends along the front and both sides of the plate, being located between the perimeter thereof and the walls of the casing. Water which collects on or passes across the 45 underside of the cover-plate will enter this groove 24, where it will collect and subsequently fall.

The bottom-plate C, has extended downward from its underside attaching-flanges 25, 26, which engage the walls of the casing, 50 the flange 25 at the rear edge of the bottom wall being secured to the rear wall 10 of the casing by screws, to thus hold said plate in position.

55 The cable-housing is centrally disposed upon said bottom-plate. Said housing is here shown as of rectangular shape in cross-section, but it may be of any other design, without departing from my invention. The lower end of the housing rests upon a centering boss 32, and is removably held in place thereon by small plates 27, see Figs. 11 and 12, which are secured to its side-walls 28 by screws 29, and which have bolt-members 30, which pass through openings formed 60 in the bottom-plate C, and receive nuts 31.

Transversely alined cable - openings 33, in the bottom-plate, lead into two compartments of the housing defined by a partition 34. As a means for securing the cables 35, against movement through the bottom-wall, 70 a block 36, is arranged at the underside of the bottom-plate, having corner-ears 37, through which screws 38, pass to secure it to said bottom-plate. Cable-openings 39, are formed in the block to aline with the openings 33. Surrounding each opening 39, is a recess 40, in the top of the block, the walls 41 of which are downwardly convergent, see Fig. 7. In each recess 40 is deposited the solder or equivalent binding material 42, 80 which is firmly packed to tie the cables to the block.

The cables may be inserted in the cable-housing after said housing has been secured upon the bottom-plate, because cables may 85 be soldered in the block 39 and then said block secured to the bottom-plate.

The panel-boards E, may be of any suitable type, it being only requisite in the present invention, that they be equipped with 90 suitable terminal connections to which the wires of the cables may be attached.

As herein shown, the panel-boards are rectangular and are mounted in parallel spaced relation to each other at opposite sides of the 95 casing A, being braced at their upper ends by means of a substantially U-shaped frame 43, the arms of which are secured to the panel-boards and the intermediate portion of which is seated in kerfs formed in the 100 upper portions of the side-walls 28 of the cable-housing.

The forward edges of the panel - boards carry conductor-plates 44, which are right angularly disposed with respect to the panel-boards, and carry the terminal contacts 45. Each panel-board is removably secured upon the bottom-plate by a pair of lugs 46 and 47, the former extending transversely upon the bottom-plate, and the latter at right angles 110 thereto. The members 46 are provided in their upper edges with a pair of spaced grooves 48 while the members 47 are each provided with a single groove 49.

Bolts 50 extend from the lower edges of 115 the panel-boards E, and the plates 44, and seat in the grooves 48 and 49 as in Figs. 1 and 2. Nuts 51 are applied to these bolts for clamping the panel-boards and plates 44 to the lugs 46 and 47, respectively.

120 Some particular advantages of my present construction are that panel-boards and cable-housing may be readily and quickly mounted upon or removed from the bottom-plate C; that this bottom-plate may be as 125 quickly and easily secured in and removed from the casing A, and that the cables may be easily inserted in the cable-housing, and properly secured against movement therein, after the bottom-wall, casing, panel-boards, 130

and cable-housing have been inserted in the casing A.

It is sometimes desirable to form the binding-block as an integral part of the bottom-plate. Such a modification is shown in Fig. 13, wherein the block 52 is cast as an integral part of the plate 52'. Cable-openings 53 are provided and solder-receiving recesses 53' are formed above and around the openings.

It may also be desirable to dispose the solder upon the upper face of the bottom-plate, as in the modified form of Fig. 14, wherein a shell or casing 54, is cast upon the upper face of the bottom-plate 55, to receive the solder or equivalent material. A cable-opening 56 is formed in the plate in concentric relation to the member 54. When the member 54 is employed, the inner 20 edges of the walls and of the cable-housing indicated at 57, by dotted lines, must be arranged as at 58, so that it will snugly engage over the member 54.

I claim:—

1. A junction-box including a casing, a cover-plate therefor, said cover-plate having marginal portions thereof extended beyond the walls of the casing, one of said walls being hingedly connected to the casing to 25 form a door to permit access to the interior of the casing, the top edge of said door closely fitting against the extended marginal portions of the cover plate and in sliding contact against the lower face of said marginal portions as said door is opened or closed, said cover-plate having a depending flange against which the door is in close contact in its closed position, and a water-deflecting groove in the lower faces 35 of the extended marginal portions between the edges thereof and the casing.

2. A junction box including a substantially rectangular casing having movable walls, a removable cover-plate therefor, said 45 cover-plate being of greater area than the cross sectional area of the casing, whereby its marginal portions overhang the walls of the casing, flanges depending from the under side of the cover-plate, one to engage 50 the outer face of one wall of the casing and others to engage the inner faces of all the walls of the casing, and a hasp for the casing.

3. A junction-box including a substantially rectangular casing, a removable cover-plate therefor, said cover-plate being of greater area than the cross-sectional area of the casing, whereby its marginal portions overhang the walls of the casing, 55 a depending flange formed on the rear edge of the cover-plate to engage against the rear-wall of the casing, parallel side-flanges depending from the cover-plate to engage against the inner faces of the side-walls of 60 the casing and a front-flange depending

from the cover-plate to engage the face of the front-wall of the casing.

4. A junction-box including a substantially rectangular casing, a removable cover-plate secured to the upper end thereof, said 70 cover-plate being of greater area than the cross-sectional area of the casing, whereby its marginal portions overhang the walls of the casing, a depending flange formed on the rear edge of the cover-plate to engage against the rear wall of the casing, parallel side-flanges depending from the cover-plate to engage against the inner faces of the side-walls of the casing and a front-flange depending from the cover-plate 75 to engage the face of the front-wall of the casing, the rear ends of said side-flanges being spaced from the said rear-flange, whereby the rear-wall of the casing is received between the terminals of the 80 side-flanges and the rear-flange, all of said side-flanges coacting to prevent the longitudinal or transverse movement of the cover-plate or upon the casing.

5. A junction-box including a casing, a 90 cover-plate therefor, a removable bottom-plate, a cable housing removably secured to said bottom-plate, panel-boards separately mounted upon the bottom-plate, and means for detachably securing the panel-boards to 95 said bottom-plate, whereby said bottom-plate, panel-boards and cable housing may be applied to or removed from the casing as a unit.

6. A junction-box including a casing, a 100 removable bottom-plate therefor, a cable-housing rising from the bottom-plate, panel boards separately and detachably mounted on said bottom plate, means removably securing the cable-housing to the bottom- 105 plate, and a cover-plate for the casing.

7. A junction-box including a casing, a removable bottom-plate therefor, a cable-housing rising from the bottom-plate, means 110 removably securing the cable-housing to the bottom-plate, panel-boards separately mounted upon the bottom-plate, means for detachably securing the panel-boards to the bottom-plate, and a cover-plate for the casing.

8. A junction-box including a casing, a removable bottom-plate therefor, a cable-housing rising from the bottom-plate, means 120 removably securing the cable-housing to the bottom-plate, panel-boards mounted upon the bottom-plate, a substantially U-shaped bracing frame connecting the upper end portions of the panel-boards and cable-housing, means for detachably securing the panel-boards to the bottom-plate, and a removable cover-plate for the casing.

9. A junction-box including a casing, a cover-plate at the upper end thereof, a bottom-plate at the bottom end thereof and having cable openings therethrough, said 130

- bottom-plate being formed with a flat lower face about said openings, and a cable-block removably secured to the bottom plate having a flat face to engage the corresponding flat face of the bottom plate in the secured position of said block, cable-openings in said cable-block registering with the cable-openings in the bottom plate in the secured position of said block to said bottom plate, said cable-block having a recess about the cable openings therein arranged to receive cables, and a solid binding material in said recess to unite the cables with said cable block, whereby the cables are supported by said cable-block from said bottom-plate.
10. A junction-box including a casing, a cover-plate at the upper end thereof, a bottom-plate removably secured to the bottom end thereof, said bottom-plate having a cable opening therein, and having a flat surface on its upper face surrounding the cable opening adapted to receive a cable-housing, a cable-housing detachably secured to said bottom-plate about the cable opening therein having a flat bottom to engage the corresponding flat face of the bottom plate in the secured position of the housing to the bottom-plate, bolts secured to the walls of said cable-housing extended
- 15 through openings in the bottom plate serving to align said cable housing in position on said bottom plate and secure said housing on said plate, and sealing material within said cable housing.
- 20 11. A junction box including a casing, a cover plate therefor, a removable bottom plate having cable receiving openings, a block removably secured to the bottom plate and provided with cable receiving openings disposed to register with cable receiving openings in the bottom plate, said cable block having recesses in its upper face which surround the cable receiving openings adapted to receive binding material to secure the cables, a cable housing rising from the bottom plate above said cable block, means for detachably securing said cable housing to the bottom plate, panel boards arranged at the sides of the housing, and means for detachably securing said panel boards to the bottom plate.
- 25 In testimony whereof I have signed my name to this specification in the presence of two subscribing witnesses.

ALFRED A. ZIEGLER.
